UNITED STATES PATENT OFFICE.

GEORGE D. EVANS, OF SHARON, PENNSYLVANIA, ASSIGNOR TO AMERICAN SHEET & TIN PLATE COMPANY, OF PITTSBURG, PENNSYLVANIA, A CORPORATION OF NEW JERSEY.

METHOD OF OPENING PACKS.

No. 874,753.

Specification of Letters Patent.

Patented Dec. 24, 1907.

Application filed March 25, 1907. Serial No. 364,473.

To all whom it may concern:

Be it known that I, GEORGE D. EVANS, of Sharon, Mercer county, Pennsylvania, have invented a new and useful Method of Opening Packs, of which the following is a full, clear, and exact description, reference being had to the accompanying drawings, forming part of this specification, in which—

Figure 1 is a sectional side elevation showing one form of apparatus for carrying out my invention, and Fig. 2 is a cross-sectional view of the same.

My invention relates to the method of opening or separating the plates or sheets of a heated pack by applying a cooling fluid or liquid thereto as set forth in the application of Charles W. Bray, No. 362,888 filed March 18th, 1907.

My invention is designed to provide a specific improvement in the said process, such improvement consisting in feeding the pack into and out of a tank of cooling liquid, such as water.

In the drawings, 2, 2 represent a pair of reducing rolls from which the pack slides over the guide 3, and upon a pair of roller chains 4, 4 movable over sprocket wheels 5 on shafts 6, 6. These chains are located in a water bosh or tank 7, which may be of any desired shape or size, and is provided with an inlet pipe 8 and an overflow pipe 9. These pipes maintain the water level at substantially that shown, so that as the pack shown at 10 is carried along by the roller chains it will be below the level of the water and be carried through the bath. The chains may be driven in any suitable manner, as for example, by a shaft 11 having a clutch driving device 12, and provided with a pinion 13 engaging a pinion 14 on a stub shaft 15, which in turn engages a toothed wheel 16 on the shaft 6. This shaft 6 at the front end of the tank is provided with a toothed wheel 17 engaging a toothed wheel 18 on a shaft 19 mounted in bearings 19' bolted to the side flanges of the tank. The shaft 19 is provided with a feed-out roller 20 which coacts with a feed-out roller 21 on the front sprocket shaft 6. From the feed-out rolls the guides 22 extend upwardly and outwardly to feed rollers or any suitable mechanism for carrying the

metal forwardly. Intermediate guides 23 and 24 may be provided for the chains in the upper and lower paths of their travel.

In carrying out my process, the pack is fed forwardly from the reducing rolls 22, and slides over the guide into the water bosh and upon the roller chains. The roller chains carry it forwardly through the water bath, where the unequal expansion and contraction of the inner and outer layers cause a drawing or pulling of the layers upon each other, which loosens the plies. The pack is then fed forwardly into the feed-out rollers, and is preferably passed forwardly to a doubling apparatus not shown, or it may be fed forward to any other desired apparatus.

The advantages of my invention result from the passing of the pack into and out of a water bosh or bath. The sudden chilling of the exterior layers of the water, and the excess of water to the side edges of the pack greatly assist in loosening and opening the pack layers.

Many variations may be made in the form and arrangement of the tank or bosh, the means for feeding in and out, &c., without departing from my invention.

I claim:—

1. In the manufacture of sheet metal, the method of opening or loosening the sheets of a pack, consisting in rolling a heated pack and then subjecting the heated pack to a cooling liquid bath; substantially as described.

2. In the manufacture of sheet metal, the method which consists in rolling a heated pack, and then feeding the heated pack through a bath of water; substantially as described.

3. In the manufacture of sheet metal, the method which consists in rolling a heated pack, then subjecting the heated pack to a liquid bath, and thereafter reducing the plates or sheets by further rolling in packed form; substantially as described.

In testimony whereof, I have hereunto set my hand.

GEO. D. EVANS.
